SEWING MACHINE

Carl F. Whitaker, Beverly, Mass., assignor to
United Shoe Machinery Corporation, Borough
of Flemington, N. J., a corporation of New
Jersey

Application May 10, 1939, Serial No. 272,771

8 Claims. (Cl. 112—59)

The present invention relates to sewing machines, more particularly shoe sewing machines, and is concerned with improvements in thread handling and supply mechanisms therefor.

5 In U. S. Letters Patent No. 1,909,157, issued May 16, 1933 to Erastus E. Winkley, there is disclosed novel and improved means for providing a sewing machine with thread from a rotatably supported spool or similar wound mass, enabling 10 the thread to be drawn off radially without variations in thread tension due to jerking and overrunning of the mass. This is accomplished, according to the patent, by providing a yielding arm for holding aside a bend of thread between the 15 rotatably supported thread mass and the stitch-forming devices, the arm yielding under a pull exerted on the thread to give up thread from the bend while the mass accelerates. When the tension on the thread relaxes, the arm, returning 20 under the action of a spring to reestablish a bend in the thread, is caused to apply a brake to retard the rotation of the thread spool and prevent overrunning thereof.

While the arrangement of the prior patent has 25 proven highly effective in supplying thread without variations in tension to the stitch-forming devices of a sewing machine during the operation thereof, certain difficulties have arisen by reason of the fact that the friction brake controlled by the yielding arm and tending to resist 30 rotation of the thread mass prevents the thread from being drawn off as freely as desired when the machine is stopped. This difficulty is particularly encountered when the devices of the 35 patent are employed with machines which sew a chainstitch seam since it is necessary in such machines that thread be given up as freely as possible when the machine is stopped to permit removal of the work without pulling out the 40 seam just sewn.

It is accordingly the object of the present invention to provide novel and improved means for providing a sewing machine with thread from a rotatably supported wound mass, enabling the 45 thread to be drawn off radially during the operation of the machine without jerking or overrunning of the mass, and arranged, upon stopping the machine to give up thread to permit removal of the work with the least possible resistance to the free withdrawal of the thread from the 50 machine.

To this end, the present invention involves the combination with a sewing machine having stitch-forming devices and control means for 55 starting and stopping the machine, of means for

rotatably supporting a wound mass of thread employed by the stitch-forming devices, a yielding arm for holding aside a bend of thread between the thread mass and the stitch-forming devices, and means actuated by the control means upon 5 stopping the machine to cause the arm to give up thread from the bend. The yielding arm, as in the patent above referred to, is arranged to control the application of a friction brake tending to resist rotation of the thread mass, and in the 10 embodiment of the invention hereinafter described, the arm is caused to give up thread from the bend upon stopping the machine without releasing the brake. When the machine is again started, the arm is actuated to reestablish 15 the bend in the thread, the arm pulling off from the supply whatever thread is needed for restoring the bend, to make up for that withdrawn in removing the work.

In the drawing illustrating the invention, 20 Figure 1 is a view in left side elevation of a chainstitch inseam shoe sewing machine in which the invention is embodied for purposes of illustration, the machine being similar in general construction and arrangement to the machine 25 shown and described in Patent No. 1,108,560 issued August 25, 1914 to Andrew Eppler, the machine having mounted thereon the devices of the invention for supporting and controlling the 30 thread mass; and Figure 2 is a rear elevation of said supporting and controlling devices alone.

In the shoe sewing machine illustrated in Figure 1, the curved hook needle is indicated at 6, the looper at 8, the thread arm at 10, and the back rest or bunter at 12, these parts, as well 35 as other instrumentalities not illustrated, being similar to those of the machine of Patent No. 1,108,560 above referred to. The machine is provided with the usual starting and stopping mechanism, controlled by foot treadle 14 acting 40 through treadle rod 16. As in the aforesaid patent No. 1,108,560, the starting and stopping mechanism is arranged to release the thread tension upon stopping the machine by relieving the pressure of brake shoe 18 on brake disk 20 45 on the tension wheel shaft 21.

The thread supply, instead of consisting of a cop or package from which the thread is drawn off endwise, employs radial delivery of the thread from a rotatably supported wound mass, avoiding 50 any tendency of the thread to kink and thus interfere with its free passage through the machine. The supporting mechanism for the thread mass is similar except as hereinafter described, to that 55

illustrated and described in the patent to Winkley No. 1,909,157 hereinbefore referred to.

The thread mass, which may be a wound spool or the like, is indicated at 22, and is fixed upon 5 a hub 24 provided at one end with a brake disc 26 and rotatably mounted by means of ball bearings 28 on the spindle 30. The spindle is received within a bore in one end of a bracket 32, the bracket having a base 34 by which the thread 10 supporting mechanism is attached at a suitable point to the machine, in the illustrative embodiment, the bracket being mounted at the top of the machine.

Secured to the spindle 30 between the bracket 15 32 and the brake disc 26 on hub 24 is a radially extending member 36 having secured in its outer end a stud 38 in parallel relation to the spindle. A sleeve 40 is rotatably mounted on the spindle, the sleeve having at one end a radially extending 20 arm 42 provided with friction material 44 adapted to engage the periphery of brake disc 26 of the thread supporting hub 24. The other end of the sleeve is provided with a boss 46 grooved to receive the two legs of a loop of wire 25 48, a cap piece 50 and bolt 52 clamping the wire to the boss. A coil spring 54 yieldingly urges the sleeve in a direction to maintain the friction brake in engagement with the brake disc 26, and to hold aside in the loop at the outer end 30 of the wire 48 a bend in the thread between the supply spool 22 and the wax pot 56.

As in the arrangement of the Winkley patent, upon a quick pull on the thread by the sewing instrumentalities, the arm 48 dips to give up 35 thread from the bend, delaying the effect of the pull on the rotatably mounted spool and thus avoiding possible breakage, until the mass has had time to accelerate free of the effect of the brake. As the pull decreases, the arm is raised 40 by the spring 54 to reestablish the bend in the thread and at the same time to cause the application of the friction brake to check the rotation 45 of the thread mass and prevent overrunning.

Although the above described arrangement 45 does not result in any substantial increase in the thread tension during the operation of the machine, nevertheless the additional tension on the thread, when the arrangement is employed in chain stitch machines, as compared with the 50 substantially tensionless withdrawal of thread endwise from a cop, has been found objectionable when the work is to be removed from the machine upon stopping. In order to allow the thread to be drawn through the machine with 55 the least possible resistance upon removing the work, as is necessary in machines of the type described which sew a chainstitch seam, the thread supporting and controlling mechanism is arranged to make available a length of thread 60 upon stopping the machine sufficient to permit the work to be removed without drawing off the thread from the wound mass.

To this end, the spindle 30, instead of being 65 fixedly mounted on the machine as in the patent to Winkley, is rotatably received within the bore in supporting bracket 32. The spindle projects beyond the bracket as shown in Figure 2, and has secured to its projecting end a short radial arm 58, a stud 60 clamping the split end of the arm 60 to secure the same on the spindle.

The arm 58 is rocked upon stopping and starting 70 the machine by treadle actuated connections comprising a rod 62 pivotally connected at its upper end to the outer end of arm 58 and at its lower end to the treadle rod 16. The rod 62 is

provided with a rearwardly and sidewardly offset portion 64 to compensate for the lack of vertical alignment of the arm 58 with the treadle rod, and also to permit the rod to clear the machine. The connection 66 between the rod 62 5 and the treadle rod 16 is in the nature of an off-set coupling, being clamped at one end to the upper portion of the treadle rod and provided at its other end with a generally vertical bore through which the rod 62 passes. Upper and 10 lower stop collars 68 and 70 permit adjustment of the rod 62 heightwise of the treadle rod, while permitting a certain degree of looseness of the parts to prevent the rod 62 from causing the treadle rod to bind.

While the machine is in operation, with the treadle in depressed position, the spindle is maintained at the limit of its rocking movement in clockwise direction, with the member 36 and the yielding arm 48 substantially in the position 20 shown in full line in Figure 1. The arm, dipping under an increased pull on the thread and rising again as the pull decreases, holds aside a bend of thread while maintaining substantially 25 uniform tension therein.

Upon stopping the machine, the treadle is permitted to rise, rocking the spindle in counter-clockwise direction to move the member 36 and the arm 48 mounted thereon to the position indicated in dot-and-dash line. Since the member 36 is mounted to rotate about a center concentric with the hub 24, i. e., both member and hub are mounted on the spindle 30, no movement of the arm 48 on its pivot 38 and relative to the member takes place as the latter is rocked, 35 and hence the friction brake 42 is not released, the hub 24 rotating as a unit with the spindle 30 and member 36. The arm 48, having been moved bodily to the position shown by the dot-and-dash line gives up thread from the bend to provide a slack loop, indicated generally at 72, adjacent the wax pot 56. The parts, and more particularly the radial arm 58, are preferably so proportioned relatively to the throw of the treadle rod 16 that the amount of slack thread 40 given up from the bend is sufficient to permit the work to be withdrawn from the machine a 45 convenient distance before cutting the thread, without requiring additional thread to be drawn off from the wound mass 22.

When the treadle is depressed by the operator to start the machine in operation, the spindle 30 is rocked to move the member 36 to its clockwise position, thus urging the arm 48 upwardly, under the action of coil spring 54, to re-establish the bend in the thread. The arm, in moving to operating position, first takes up whatever slack thread was not pulled from the machine when the work was removed at the end of the previous sewing operation. Thereafter, any additional thread to make up for that previously withdrawn with the work is pulled off from the supply, the pull on the thread causing the arm 48 to release the friction brake arm 42 and permit the wound mass to rotate to give up whatever thread is needed for the reestablishment of the bend.

While the invention has been illustrated and described as embodied in a particular type of sewing machine, it is evident that the invention may be employed to advantage in sewing machines of other types and arrangements where it is desirable that the thread be supplied radially from a wound mass under uniform tension and without overrunning of the mass, while per-

mitting the work to be removed when the machine is stopped without hindering to the slightest degree the free withdrawal of the thread.

Having thus described the invention, in its preferred form, and an embodiment thereof having been illustrated, what is claimed is:

1. A sewing machine having, in combination, stitch-forming devices, control means for starting and stopping the machine, means for rotatably supporting a wound mass of thread employed by the stitch-forming devices, a yielding arm for holding aside a bend of thread between the thread mass and the stitch-forming devices, and means actuated by the control means upon stopping the machine to cause the yielding arm to give up thread from the bend.

2. A sewing machine having, in combination, stitch-forming devices, control means for starting and stopping the machine, means for rotatably supporting a wound mass of thread employed by the stitch-forming devices, a yielding arm for holding aside a bend of thread between the thread mass and the stitch-forming devices, frictional braking means controlled by the yielding arm for resisting rotation of the thread mass, and means actuated by the control means upon stopping the machine to cause the yielding arm to give up thread from the bend.

3. A sewing machine having, in combination, stitch-forming devices, control means for starting and stopping the machine, means for rotatably supporting a wound mass of thread employed by the stitch-forming devices, a yielding arm for holding aside a bend of thread between the thread mass and the stitch-forming devices, frictional braking means controlled by the yielding arm for resisting rotation of the thread mass, and means actuated by the control means upon stopping the machine to cause the yielding arm to give up thread from the bend while maintaining the frictional braking means effective to resist rotation of the thread mass.

4. A sewing machine having, in combination, stitch-forming devices, control means for starting and stopping the machine, means for rotatably supporting a wound mass of thread employed by the stitch-forming devices, a yielding arm for holding aside a bend of thread between the thread mass and the stitch-forming devices, and means actuated by the control means upon stopping the machine to cause the arm to give up thread from the bend, and upon starting the machine to cause the arm to reestablish the bend in the thread.

5. A sewing machine having, in combination, stitch-forming devices, control means for starting and stopping the machine, means for rotatably supporting a wound mass of thread employed by the stitch-forming devices comprising a hub upon which the wound mass is fixed and a spindle on which said hub is rotatably mounted, an arm carried by the spindle for holding aside a bend of thread between the thread mass and the stitch-forming devices, and means actuated by the con-

trol means upon stopping the machine to rock the spindle to cause the arm to give up thread from the bend.

6. A sewing machine having, in combination, stitch-forming devices, control means including a treadle for starting and stopping the machine, means for rotatably supporting a wound mass of thread employed by the stitch-forming devices comprising a hub upon which the wound mass is fixed and a spindle on which the hub is rotatably mounted, a yielding arm carried by the spindle for holding aside a bend of thread between the thread mass and the stitch-forming devices, frictional braking means controlled by the yielding arm for resisting rotation of the hub relative to the spindle, and treadle operated connections for rocking the spindle upon stopping the machine to move the yielding arm bodily to cause thread to be given up from the bend while maintaining the frictional braking means effective to resist rotation of the thread mass.

7. A sewing machine having, in combination, stitch-forming devices, control means for starting and stopping the machine, means for rotatably supporting a wound mass of thread employed by the stitch-forming devices comprising a hub on which the wound mass is fixed and a spindle on which the hub is rotatably mounted, a member secured to the spindle, an arm pivotally mounted on said member, the arm being adapted yieldingly to hold aside a bend of thread between the thread mass and the stitch-forming devices, frictional braking means carried by the member and controlled by the arm for resisting rotation of the hub relative to the spindle, and means actuated by the control means upon stopping the machine to rock the spindle and thereby to move the arm bodily to cause thread to be given up from the bend while maintaining the frictional braking means effective to resist rotation of the thread mass.

8. A sewing machine having, in combination, stitch-forming devices, control means including a treadle for starting and stopping the machine, means for rotatably supporting a wound mass of thread employed by the stitch-forming devices comprising a hub on which the wound mass is fixed and a spindle on which the hub is rotatably mounted, a member mounted concentrically with the spindle, an arm pivotally mounted on the member and adapted yieldingly to hold aside a bend of thread between the thread mass and the stitch-forming devices, frictional braking means controlled by the yielding arm for resisting rotation of the hub relative to the member, and means actuated by the treadle upon stopping the machine for rocking the member in a direction to cause the arm to give up thread from the bend while maintaining the frictional braking means effective to resist rotation of the thread mass, and upon starting the machine to rock the member in the opposite direction to cause the arm to re-establish the bend in the thread.

CARL F. WHITAKER.
